US00D710610S

(12) **United States Design Patent**
Sijmons et al.

(10) **Patent No.:** US D710,610 S
(45) **Date of Patent:** ** Aug. 12, 2014

(54) **LUGGAGE**

(71) Applicant: **Samsonite IP Holdings S.a r.l.**,
Luxembourg (LU)

(72) Inventors: **Erik Sijmons**, Oudenaarde (BE); **Lucie
Boddaert**, Marcq-en-Baroeul (FR)

(73) Assignee: **Samsonite IP Holdings S.arl.**,
Luxembourg (LU)

(**) Term: **14 Years**

(21) Appl. No.: **29/469,822**

(22) Filed: **Oct. 15, 2013**

(51) LOC (10) Cl. **03-01**

(52) U.S. Cl.

USPC **D3/279; D3/321**

(58) **Field of Classification Search**

USPC D3/272, 276, 278, 279, 273, 274, 281,
D3/289, 321; 190/100-127, 903, 37, 39,
190/18 A

(74) *Attorney, Agent, or Firm* — Dorsey & Whitney LLP

(57) **CLAIM**

The ornamental design for luggage, as shown and described.

DESCRIPTION

FIG. 1 shows a front perspective view of luggage;
FIG. 2 shows a front elevation view of the luggage of FIG. 1;
FIG. 3 shows a rear elevation view of the luggage of FIG. 1;
FIG. 4 shows a right elevation view of the luggage of FIG. 1;
FIG. 5 shows a left elevation view of the luggage of FIG. 1;
FIG. 6 shows a top view of the luggage of FIG. 1; and,
FIG. 7 shows a bottom view of the luggage of FIG. 1.
In FIGS. 1-7, the broken lines and the unshaded areas therein
illustrate portions of the luggage and form no part of the
claimed invention.

1 Claim, 7 Drawing Sheets
